UNITED STATES PATENT OFFICE.

CHARLES F. CHOUFFET, OF NEW YORK, N. Y., ASSIGNOR TO WM. L. GILBERT CLOCK COMPANY, OF WINSTED, CONNECTICUT, A CORPORATION OF CONNECTICUT.

DESIGN FOR A CLOCK.

• 44,399.

Specification for Design.

Patented July 29, 1913.

Application filed May 6, 1913. Serial No. 765,929. Term of patent 3½ years.

To all whom it may concern:

Be it known that I, CHARLES F. CHOUFFET, a citizen of the United States, residing at New York city, in the county and State of New York, have invented a new, original, and ornamental Design for Clocks, of which the following is a specification, reference being had to the accompanying drawing, forming part thereof.

The figure shown is a view in elevation of a clock showing my new design.

What I claim is:

The ornamental design for a clock, as shown.

CHARLES F. CHOUFFET.

Witnesses:

E. E. MORSE,
FLORENCE G. HADLEY.
